UNITED STATES PATENT OFFICE.

ORA A. COLBY, OF LARIMER, PENNSYLVANIA, ASSIGNOR TO WESTINGHOUSE ELECTRIC AND MANUFACTURING COMPANY, A CORPORATION OF PENNSYLVANIA.

ELECTRIC HEATING APPARATUS.

1,332,029.

Specification of Letters Patent. Patented Feb. 24, 1920.

Application filed September 21, 1916. Serial No. 121,428.

To all whom it may concern:

Be it known that I, ORA A. COLBY, a citizen of the United States, and a resident of Larimer, in the county of Westmoreland 5 and State of Pennsylvania, have invented a new and useful Improvement in Electric Heating Apparatus, of which the following is a specification.

My invention relates to electric heating 10 apparatus such as air heaters, oven heaters and other devices in which the resistance conductors are exposed to the air, and it has for its object to provide an electric heater of the above-indicated character which shall 15 be simple and inexpensive in construction and in which the resistance conductor shall be arranged in a novel manner in order to increase the efficiency and the effective life of the apparatus.

20 In the accompanying drawing, Figure 1 is a side elevational view, with parts shown in section, of an electric air heater constructed in accordance with my invention, and Fig. 2 is an end elevational view with 25 parts broken away and shown in section, of the structure shown in Fig. 1.

The heating device shown in the drawing comprises a sheet-metal frame supported upon legs 1 and consisting of top and bottom plates 2 and 3 and sides 4 and 5, which together form a box-like structure open at the front and rear. Supported centrally and vertically within the frame is a partition formed of one or more sheets 6 of asbestos lumber or other suitable insulating 35 material. The sheets 6 are fastened in place, as shown, by means of parallel horizontal rods 7 and 8 which extend lengthwise of the heater and to which the upper and 40 lower edges of the sheet 6 are attached by means of suitable fasteners 9.

The vertical insulating partition is provided with perforations arranged in four rows 10, 11, 12 and 13, through which a resistance coil 14 is passed in a series of zig-zag sections. It will be observed that the rows of perforations are staggered so as to bring the two zig-zag resistance sections in each half of the device into staggered parallel 45 relation. It will also be observed that half of the straight portions of each resistance section are disposed on one side of the insulating sheet 6 and the other half on the other side and that the adjacent parallel 50 portions of the two sections are disposed on

opposite sides of the insulating sheet and are thereby maintained out of direct communication and prevented from heating one another by mutual radiation.

It will be noted that the rising air current 60 in the immediate vicinity of the heating coils travels upwardly along the insulation sheet 6 and passes over a single heating conductor in its course. The stream of heated air, leaving a lower zigzag section of heating coil 14, passes up between the two adjacent upper sections without loss of heat to either of these upper sections which are themselves traversed by unheated streams of air from the positions immediately beneath 70 them.

The arrangement of the coils which I have just described is a feature of particular advantage over prior heating devices having exposed coils, because, in such prior 75 devices, it has been the practice to dispose the several coils so near to one another that much of the heat radiated from the coils is absorbed by the adjacent coils instead of being communicated to the surrounding atmosphere. This causes both loss in effective 80 heating power and overheating of the resistance conductors which materially shortens their effective life.

The several resistance coils may be connected and supplied with current in any suitable manner. As shown, connection to line conductors is made by means of conductors 15 and 16 which extend, in a cord 17, through a bushing 18 in the rear wall of the 90 device. The conductors 15 and 16 are led to a snap switch 19 which may be of any suitable construction and is centrally disposed at the front of the heater. One of the terminals of the snap switch 19 is connected, by 95 means of conductors 20 and 21, to binding screws 22 and 23 at opposite ends of the insulating sheet 6, these binding screws also serving to connect the four sections of resistance conductors in two parallel groups. 100 The inner or central ends of the four resistance coils are connected to terminals 27 and 24, which are, in turn, connected, by means of conductors 25 and 26, to another terminal of the snap switch 19. 105

It is obvious that the switch 19 may be arranged to energize either a part or all of the resistance coils and that the several coils may, if desired, be connected for operation either in series or in parallel relation. It 110

will also be understood that various structural modifications may be effected in the apparatus which I have shown and described without exceeding the limits of my invention 5 or the scope of the appended claims.

I claim as my invention:

1. An electric air heating device comprising a plurality of zig-zag sections of resist-
10 ance material exposed to the air and ar-
ranged vertically with their several bent
portions substantially parallel, and means
for maintaining the vertically adjacent par-
allel portions of the said sections out of di-
rect communication, so that the rising
15 column of air will be heated but once in pass-
ing two sections.

2. An electric air heating device comprising
19 a perforated sheet of insulating material
arranged in a vertical plane and a resist-
20 ance conductor extending, in zig-zag ar-
rangement, through the perforations in the
said sheet in such manner that the contig-
uous portions in a horizontal direction lie
25 on opposite sides of said perforated sheet, so
that the rising column of air will be heated
but once in passing two sections.

3. An electric air heating device comprising
a frame, a perforated sheet of insulating
material supported vertically thereby, and a
30 resistance conductor extending, in zig-zag
arrangement, through the perforations in

the said insulating sheet in such manner that
the contiguous portions in a horizontal di-
rection lie on opposite sides of said perfo-
rated sheet, so that the rising column of air 35
will be heated but once in passing two sec-
tions.

4. An electric air heating device comprising
a vertically disposed sheet of insulating
material provided with a plurality of spaced 40
rows of perforations, and a resistance con-
ductor extending, in parallel zig-zag ar-
rangement, through the said perforations,
the adjacent parallel portions of the said
conductor being disposed on opposite sides 45
of the said insulating sheet in a manner to
prevent mutual radiation therebetween, so
that the rising column of air will be heated
but once in passing two sections.

5. An electric heating device comprising 50
a vertically disposed sheet of insulating ma-
terial carrying two resistance conductors ex-
tending in zigzag formation in a horizontal
direction upon the sheet and so arranged,
55 one above the other, that the vertically cor-
responding portions lie on opposite sides of
said sheet of insulating material.

In testimony whereof, I have hereunto
subscribed my name this 7th day of Sept.,
1916.

ORA A. COLBY.
